CLAIM

The ornamental design for a folding shelf, as shown and described.

DESCRIPTION

FIG. 1 is a top perspective view of a folding shelf including a flat wire shelf;

FIG. 2 is a front view of the folding shelf of FIG. 1, the opposing back view being a mirror image thereof;

FIG. 3 is an end view of the folding shelf of FIG. 1, the opposing end view being a mirror image thereof;

FIG. 4 is a top view of the folding shelf of FIG. 1;

FIG. 5 is a bottom view of the folding shelf of FIG. 1;

FIG. 6 is a bottom perspective view of the folding shelf of FIG. 1;

FIG. 7 is another bottom perspective view of the folding shelf of FIG. 1 with enlargement regions indicated;

FIG. 8 is an enlarged view of the region within circular axis 8 of FIG. 7;

FIG. 9 is an enlarged view of the region within circular axis 9 of FIG. 7;

FIG. 10 is a top perspective view of a folding shelf including a round wire shelf;

FIG. 11 is a front view of the folding shelf of FIG. 10, the opposing back view being a mirror image thereof;

FIG. 12 is an end view of the folding shelf of FIG. 10, the opposing end view being a mirror image thereof;

FIG. 13 is a top view of the folding shelf of FIG. 10;

FIG. 14 is a bottom view of the folding shelf of FIG. 10;

FIG. 15 is a bottom perspective view of the folding shelf of FIG. 10;

FIG. 16 is another bottom perspective view of the folding shelf of FIG. 10 with enlargement regions indicated;

FIG. 17 is an enlarged view of the region within circular axis 17 of FIG. 16; and,

FIG. 18 is an enlarged view of the region within circular axis 18 of FIG. 16.
